UNITED STATES PATENT OFFICE

2,409,056

SOAP COMPOSITION

Herbert Kenneth McClain, Wyoming, Ohio, assignor to The Procter and Gamble Company, Ivorydale, Ohio, a corporation of Ohio

No Drawing. Application August 22, 1944,
Serial No. 550,671

8 Claims. (Cl. 252—368)

1

This invention relates to the stabilization of soap or soap products, and more particularly to the prevention or retardation of the development of rancidity and customary accompanying discoloration.

It is an object of the present invention to improve the quality of soap products, especially with respect to their keeping quality as evidenced by their tendency to become rancid or discolored.

It is known that many soap products will discolor and develop a rancid odor on aging and that this property is especially characteristic of soap products prepared from fats which themselves are susceptible to the development of rancidity. These undesirable changes in the soap product are in part due to conditions of storage and handling, but in the main the development of rancidity is more pronounced in products which have become contaminated during processing with a small amount of an agent such as copper for example, which will promote rancidity.

Many preservatives have been suggested for use in the prevention or retardation of the development of rancidity in such soaps, and their effectiveness has been well established.

Recently, because of fat shortages, it has become necessary to supplement normal fat requirements for soap manufacture with rosin and the use of this material has introduced problems in rancidity which have not heretofore been encountered. For example, it has been noted that soap products in particle form such as flakes, spray dried granules, etc., having a relatively large surface area per unit weight and a relatively low moisture content and prepared from fat mixtures containing rosin, develop undesired rancidity and accompanying discoloration much faster than do similar products prepared from comparable fat formulas containing no rosin. The amount of rosin does not appear critical. Small amounts such as 1 per cent to 2 per cent will enhance the development of rancidity in the soap products prepared from such mixtures, and larger amounts will have even greater effect. I have discovered further that such soap products containing rosin soap are not suitably preserved against the development of rancidity by agents which have been effectively used heretofore in ordinary soap products. As a matter of fact, I have obtained evidence indicating that some of the preservatives which are effective in retarding the development of rancidity in ordinary soap granules and flakes, for example, actually promote the development of rancidity in

2

those products containing a proportion of rosin soap.

According to my invention polyethylene polyamines of the formula

wherein x is a whole number of 1 or more effectively prevent or retard to a desired degree the development of rancidity in soap products and especially those which contain a proportion of rosin soap and which are readily susceptible to the development of rancidity. Of the polyethylene polyamines referred to, those in which the value of x is from 1 to 5 are particularly well suited for use in the practice of the invention. Of outstanding value as preservatives are diethylene triamine, triethylene tetramine and tetraethylene pentamine, that is, those polyamines having x values of 1, 2 and 3 respectively. Commercial mixtures of these various amines may also be employed with good effect.

In the range of ordinary conditions, I find that an amount of the polyethylene polyamine which will give good results will be from about 0.02 per cent to about 0.1 per cent of the weight of the soap. Amounts above and below this range, however, such as 0.005 per cent to 1 per cent of the weight of the soap will show preservative action also and may be employed if desired.

In producing the stable soap products of the present invention the preservative is added to the soap in any convenient manner during the usual crutting or other mixing operation wherein the preservative will be uniformly distributed throughout the entire soap mass. Distribution may be assisted by dissolving the amine in a carrier, but I have found that this is unnecessary and that effective distribution may be brought about in the same manner that is used in distributing perfume or other ingredients throughout the soap mass. After the polyethylene polyamine has been thoroughly admixed with the soap, the mixture is converted into the desired product form.

The effective preservative action of the polyethylene polyamines is noted in soap products of all kinds, but, as previously pointed out, their outstanding value lies in their use in granular type soap products containing a proportion of rosin soap.

The following examples will illustrate the manner in which my invention may be practiced, but it is to be understood that the invention is not to be limited to the specific conditions recited therein.

Example 1.—A mixture consisting of 86.7% of combination of tallow and grease having a titer in the neighborhood of 40 and 13.3% rosin was converted into kettle soap in the usual way by treatment with caustic soda solution. After the usual boiling and washing operations, the kettle soap was crutched, during which 0.05% by weight of triethylene tetramine was uniformly distributed throughout the soap mass. A spray dried soap product was prepared from this mixture in the usual manner, for example as disclosed in United States Patent No. 1,652,900. In an accelerated rancidity development test involving exposure of the spray dried product for three days at 120° F. to the atmosphere, the product developed a peroxide value of 2.5. A spray dried product corresponding in every way with the sample prepared above except that the triethylene tetramine was omitted developed a peroxide value of 58 under the same test. These peroxide values, translated into results of shelf storage tests under normal conditions, indicate that the product without preservative will go rancid in one month whereas the product containing the preservative will stay fresh for many months.

Example 2.—A mixture of 95% of a combination of tallow and grease having a titer in the neighborhood of 40 and 5% rosin was saponified in the kettle with caustic soda solution, then boiled and washed in the customary manner. In the crutting operation 0.10% by weight of triethylene tetramine was uniformly distributed throughout the soap mass. Thereafter the soap was converted into thin flake form, for example by the flake forming process disclosed in United States Patent No. 2,295,596. In the accelerated rancidity development test described in Example 1 the soap flakes developed a peroxide value of 0.4 and remained fresh for many months in a shelf storage test whereas a product corresponding in every way except that it contained no triethylene tetramine preservative developed a peroxide value of 9.0 in the accelerated test and became rancid in about one month in the shelf storage test.

Soap products prepared from fat formulas other than that shown in the example will also be improved by the addition of the polyethylene polyamine preservatives of my invention. Thus the invention may be employed to advantage in the production of soap products from rosin-containing formulas including various tallow and greases, coconut oil, cottonseed foots fatty acid, etc.

I have also found in the course of my work on the invention that the mineral acid salts, for example, the sulfates of the polyethylene polyamines above referred to likewise have preservative action comparable with that of the amines themselves when incorporated with the soap, and the invention is to be understood as including their use. The chlorides, phosphates, etc., of the amines may also be incorporated if desired.

Having thus described my invention, what I claim and desire to secure by Letters Patent is:

1. The process of inhibiting the development of rancidity and discoloration in a granular soap product prepared from a fat formula containing a minor proportion of rosin, which comprises incorporating with the soap a polyethylene polyamine of the formula

wherein x is a whole number from 1 to 3.

2. A soap product comprising essentially soap

of which a minor proportion is rosin soap and, as a rancidity and discoloration inhibitor, a polyethylene polyamine of the formula

5 x being a whole number, the said product being in small particle form and having a relatively large surface area per unit weight and a relatively low moisture content substantially corresponding to that of flake and spray dried granular soap products.

10 15 3. A soap product comprising essentially soap of which a minor proportion is rosin soap and, as a rancidity and discoloration inhibitor, from about 0.005 per cent to about 1 per cent by weight of a polyethylene polyamine of the formula

20 25 wherein x is a whole number from 1 to 5, the said product being in small particle form and having a relatively large surface area per unit weight and a relatively low moisture content substantially corresponding to that of flake and spray dried granular soap products.

30 35 4. A soap product comprising essentially soap of which a minor proportion is rosin soap and, as a rancidity and discoloration inhibitor, from about 0.005 per cent to about 1 per cent by weight of diethylene triamine, the said product being in small particle form and having a relatively large surface area per unit weight and a relatively low moisture content substantially corresponding to that of flake and spray dried granular soap products.

40 45 5. A soap product comprising essentially soap of which a minor proportion is rosin soap and, as a rancidity and discoloration inhibitor, from about 0.005 per cent to about 1 per cent by weight of triethylene tetramine, the said product being in small particle form and having a relatively large surface area per unit weight and a relatively low moisture content substantially corresponding to that of flake and spray dried granular soap products.

50 55 6. A soap product comprising essentially soap of which a minor proportion is rosin soap and, as a rancidity and discoloration inhibitor, from about 0.005 per cent to about 1 per cent by weight of tetraethylene pentamine, the said product being in small particle form and having a relatively large surface area per unit weight and a relatively low moisture content substantially corresponding to that of flake and spray dried granular soap products.

60 65 7. A soap product in flake form comprising essentially soap of which a minor proportion is rosin soap and, as a rancidity and discoloration inhibitor, from about 0.02 per cent to about 0.1 per cent by weight of a polyethylene polyamine of the formula

wherein x is a whole number from 1 to 3.

65 70 8. A soap product in spray dried form comprising essentially soap of which a minor proportion is rosin soap and, as a rancidity and discoloration inhibitor, from about 0.02 per cent to about 0.1 per cent of a commercial mixture of polyethylene polyamine consisting essentially of amines of the formula

wherein x is a whole number from 1 to 3.

HERBERT KENNETH McCALIN.
